UNITED STATES PATENT OFFICE.

CHARLES P. KIMMEL, OF GARY, INDIANA.

RAIL-HOLDING DEVICE.

Application filed June 24, 1926. Serial No. 118,200.

My invention relates to rail holding devices, and particularly to a novel boltless rail joint or rail anchor having new and useful functions.

5 An object of my invention is to provide a rail holding device in which bolts are unnecessary; in which, when used as a rail joint, the base of the rail is closely held throughout a substantial distance at each 10 side of the joint; in which the vertical load on the head of the rail is transmitted directly through an angle bar or the fish plate to the base without tending to spread or force out the angle bar from its position alongside 15 the web.

In the construction commonly in use, the wheel load at the end of a rail is transmitted to the angle bar underneath the head. The load is thence transmitted by the bar to the 20 flange, the taper of which is downward and outward. Thus one component of the force is horizontal and tends to elongate the fastening bolts and to loosen the nuts. An object in the present construction is to reverse the direction of force of the horizontal component and to effect the clamping 25 action without the use of any fastening bolts.

The device, when used as a rail joint, 30 comprises essentially, a long shoe, constructed to underlie the rail base and having angular abutments that overlie the base and are co-extensive in length with the underlying portion. Cooperating with the shoe 35 and particularly with the overlying abutments are angle bars, the heads of which underlie the head of the rail and the lower surfaces of which are longitudinally inclined and engage the oppositely inclined upper 40 surfaces of the abutments. The longitudinally tapered contacting surfaces are likewise inclined to the horizontal, the angle being acute to the angle of the under surface of the head. The additional elements are 45 rail holding bars having projections entering the usual bolt holes in the rail web, the last named bars being held in place by the angle bars.

A device of this character has many advantages that will be pointed out in the 50 appended description.

The invention will be more readily understood by reference to the accompanying drawings, in which;

55 Fig. 1 is a side elevation of a rail joint

constructed in accordance with my invention;

Fig. 2 is a plan section on the line 2—2 of Fig. 3;

Fig. 3 is an end view with the rail in section;

Fig. 4 is an end view of a modification of the construction shown in the preceding figures;

Fig. 5 is a side view thereof, and

Fig. 6 is an end view of a further modification, the plate and abutment being shown in the form in which they are applied to the rail, the angle bar being omitted.

Referring particularly to the drawing, it will be seen that I provide a base member or shoe having a flat base plate, 10, that extends a substantial distance beyond the meeting edges of the rails, indicated at A. The shoe has the usual lateral flanges, 10^a, 75 containing spike holes, 10^b. Integral with the base plate and extending upwardly therefrom are continuous ribs, 13, and integral therewith are the abutment members, 14. The abutments have two surfaces, 15, 16, 80 arranged at an acute angle, the surface, 16, being longitudinally inclined or tapered. It is to be noted that the wedge surfaces, 16, of the abutments on opposite sides of the shoe are oppositely longitudinally inclined. 85 Bounding the inclined surfaces, 16 at the outer edge of the abutment member is a lip, 17, extending throughout the length of the abutment.

The angle bars, indicated generally by the 90 numeral 18, have a bulbous head, 19, the upper and inner surfaces of which correspond to and cooperate with the surfaces underneath the rail head and alongside of the web at its junction with the head. The 95 inner face of the angle bar is grooved to accommodate the rail holding bars to be later described. The bottom surface 20, of the angle bar is tapered to conform to the inclined or wedge surface, 16 of the abutment, a continuous lip, 21, extending at the lower extremity of the angle bar and overlying the lower extremity of the surface, 16. It will be noted that the surfaces, 16 and 20 100 are disposed at an angle to the horizontal, and at an acute angle to the surface underneath the rail head. The result of this is that a downwardly directed force applied to the rail head tends to move the angle bar 105 inwardly instead of outwardly as in the 110

usual construction where the angle bar rests on the top surface of the rail base. A further result of this arrangement is that when the angle bars are driven into position, the wedge force tends to move the bar inwardly against the rail flanges rather than outwardly.

The rail holding bars indicated generally by the numerals, 22, 23, are duplicates, each thereof comprising a body portion and two round lugs or projections, 24. The bars are placed in staggered relation, one lug, 24, entering an opening in each rail. One extremity, 25, of each bar is tapered off and may be swedged over if desired in order to prevent possible loosening up and backing out of the angle bars. Such loosening, however, is a remote possibility, inasmuch as the taper of the wedge surface is very slight.

20 The assembly of the parts is very simple. The shoe with the abutment members somewhat spread or elevated, is placed over the end of a rail and the second rail located in proper relation thereto, after which the shoe 25 may be spiked in position and the abutments bent downward into contact with the rail base. The rail holding bars are then located as shown and the angle bars slid inward longitudinally and driven home by 30 means of a sledge. Thereafter the ends, 25, of the rail bars may be bent over if desired.

If it is necessary to remove the assembly, the series of operations is reversed. However, the shoe may be found to be tightly 35 clamped on the rail base, and the lip, 17 at the margin of the abutments is adapted to be engaged by a suitable tool for the purpose of bending the abutments out and releasing them from the rail flange.

40 One of the functional advantages of the construction is the facility with which the entire assembly may be moved, thereby providing new points of contact or bearing surfaces between the rails and the joint assembly. To do this, it is only necessary to back out the wedge angle bars and thereafter move the shoe a short distance one way or the other, the angle bars being subsequently driven tight. This may be done several 45 times if desired in order to provide new points of contact.

In the modification shown in Figs. 4 and 5, the device is utilized as a rail anchor, the same principles being applied. In that construction, the base member, 26, is provided with similar abutment members, 27, and at each corner the base member is deflected or turned down as at 28, to provide lugs engaging the opposite faces of a tie, indicated 50 at B.

60 Wedge shaped angle bars, 29, are provided that are driven into place between the head of the rail and the abutments, and when so positioned, serve to securely lock the rail 65 and tie and to prevent creeping. It may be

desirable to provide the taper on the angle bars in the same direction on both sides, and to apply the device so that the creeping tendency of the rail will further increase the wedging action, and the construction is 70 so shown.

In the modification shown in Fig. 6, the base plate, 30 is identical, together with the downturned lugs, 31. However, I have provided but one abutment member, 32, the rail 75 being held at the opposite side by a rib, 33. In this construction, the device may be assembled without sliding it on the rail from the end; in other words, it may be placed or removed at any point on the rail. To 80 accomplish this result the abutment, 32, is positioned as shown in Fig. 6, the rail being shown in dotted lines. When suitably positioned, the abutment is bent down by striking it with a sledge.

In both of the forms just described, no rail holding bars are used, inasmuch as the web of the rail is not punched at points between its ends.

Many other modifications will undoubtedly suggest themselves to those skilled in the art, and I do not wish to be limited except as indicated in the appended claims.

I claim:

1. In a rail joint, the combination of a shoe enclosing the bases of two abutting rails, an abutment member carried by the shoe and overlying the rail base, a bar having contact with the under surface of the rail head and the upper surface of the abutment, the contacting surfaces of the bar and abutment being mutually longitudinally inclined to provide wedge action, and positively acting means to prevent longitudinal separation of the respective rails.

2. In a rail joint, the combination of a shoe enclosing the bases of two abutting rails, an abutment member carried by the shoe and overlying the rail base, a bar having contact with the under surface of the rail head and the upper surface of the abutment, the contacting surfaces of the bar and abutment being mutually longitudinally inclined to provide wedge action, said surfaces being arranged at an angle to the horizontal that is acute relative to the angle of inclination of the under surface of the rail head.

3. In a rail joint, the combination of a shoe enclosing the bases of two abutting rails, an abutment member carried by the shoe and overlying the rail base, a bar having contact with the under surface of the rail head and the upper surface of the abutment, the contacting surfaces of the bar and abutment being mutually longitudinally inclined to provide wedge action, said surfaces being arranged at an angle of substantially 45 degrees to the angle of the upper surface of the rail flange.

4. In a rail joint, the combination of a

shoe adapted to receive a rail flange, an abutment overlying the flange, the upper surface of the abutment being inclined downwardly and inwardly toward the rail web, a bar having contact with the under surface of the rail head and the upper surface of the abutment, the contacting surfaces of the bar and abutment being reversely inclined to provide wedge action.

5. In a rail joint, the combination of a base plate for supporting a rail flange and coextensive abutment members overlying the flange, the abutment members being substantially triangular in cross section, with the upper surface arranged at an angle of approximately 45 degrees to the lower surface, and a bar occupying the fishing surface of the rail, said bar having a longitudinally tapered surface cooperating with the upper surface of an abutment member, the thrust resulting from the wedge action of the bar tending to move the bar inwardly toward the rail web.

6. In a rail joint, the combination of a base plate for supporting a rail flange and coextensive abutment members overlying the flange, the abutment members being substantially triangular in cross section, with the upper surface arranged at an angle of approximately 45 degrees to the lower surface, a bar occupying the fishing surface of the rail, said bar having a longitudinally tapered surface cooperating with the upper surface of an abutment member, the thrust

resulting from the wedge action of the bar ³⁵ tending to move the bar inwardly toward the rail web, and means retained in position positively holding abutting rails against longitudinal separation.

7. In a rail joint, the combination of a base plate for supporting a rail flange and coextensive abutment members overlying the flange, the abutment members being substantially triangular in cross section, with the upper surface arranged at an angle of approximately 45 degrees to the lower surface, a bar occupying the fishing surface of the rail, said bar having a longitudinally tapered surface cooperating with the upper surface of an abutment member, the thrust ⁴⁵ ⁵⁰ resulting from the wedge action of the bar tending to move the bar inwardly toward the rail web, and means for positively preventing the backing out of said bar.

8. In a device of the class described, the combination of a shoe adapted to receive a rail base, an abutment overlying one flange of the rail base, the upper surface of the abutment being inclined downwardly and inwardly toward the rail web, and a wedge ⁵⁵ ⁶⁰ shaped angle bar adapted to be driven longitudinally into the space between the under-surface of the rail head and the upper surface of the abutment.

In testimony whereof I have affixed my ⁶⁵ signature.

CHARLES P. KIMMEL
